UNITED STATES PATENT OFFICE

GEORGE KATEB, OF NEW YORK, N. Y.

DESIGN FOR A WOVEN SILK FABRIC OR SIMILAR ARTICLE

Application filed February 27, 1931. Serial No. 38,846. Term of patent 3½ years.

To all whom it may concern:

Be it known that I, GEORGE KATEB, a citizen of the United States, residing at New York, in the county of New York and State of New York, have invented a new, original, and ornamental Design for Woven Silk Fabric or Similar Article, of which the following is a specification, reference being had to the accompanying drawing, forming a part thereof.

The figure of the drawing is a plan view of a piece of woven silk fabric showing substantially one complete unit of the design, which unit is repeated throughout the extent of the fabric in regular succession.

I claim:

The ornamental design for a woven silk fabric or similar article, as shown and described.

GEORGE KATEB.
